METHOD OF MAKING REINFORCED CHIME CONSTRUCTION FOR CANS OR CONTAINERS

Louis B. Wackman, Richmond Heights, Mo.

Application May 7, 1943, Serial No. 485,978

2 Claims. (Cl. 113—121)

This invention relates to a method of making a reinforced chime construction for cans or containers.

An object of the invention is to provide a method of making a can or container chime of parts which are folded together in a manner so as to present a flush outer surface on the container wall.

A further object is to provide a method of making a chime of an improved construction to containers having permanently secured counter-sunk heads.

Another further object is to provide a method of making an improved chime at both ends of a container by folding parts of the heads and the container wall together without the application and use of a crimping ring.

The invention also pertains to the end construction of containers presently made of sheet metal and the invention in particular residing in the manner of uniting the heads to the container body to provide improved chime ends thereto and to further reinforce the container adjacent its ends by beading to form a seal-tight joint between the heads and container body.

Other and further advantages will appear as this description progresses and by reference to the drawing, in which—

Figure 1 is a vertical sectional elevation through the upper end of a container showing this improved reinforced chime construction applied thereto.

Figure 2 is an enlarged fragmentary sectional portion of one of the container heads showing the first step in the formation thereof to adapt it for securing cooperation with the container body.

Figure 3 is an enlarged fragmentary sectional elevation showing the second step in the formation of the head portion shown in Fig. 2.

Figure 4 is an enlarged fragmentary sectional elevation through the upper portion of the container body wall showing the step required in forming an outwardly and downwardly disposed annular flange in readiness for the head insertion therein in the manner as shown in Fig. 5.

Figure 4a is an enlarged fragmentary sectional elevation through the upper portion of the container head showing a further step of downwardly deflecting the preformed flange of the head for engagement with the container body wall flange, as shown in Fig. 5.

Figure 5 is an enlarged fragmentary sectional elevation showing the head inserted in the upper

end of the container body and having the head flange engaged against the body flange.

Figure 6 is an enlarged fragmentary sectional elevation showing the last steps of folding the flanges of the head and body wall together, in crimped security, to form the chime and to provide a seal-tight joint between the head side wall and the body wall.

Referring by numerals to the accompanying drawing, the body 7 of the container has a counter-sunk head 8 with the extending end of the side wall 9 in folded and crimped security with the body wall 11a, at the upper end thereof to provide the improved container chime 10, shown in Figs. 1 and 6.

As both the upper and lower heads of the container are similar and are secured to the container body wall in the same manner, only the upper head 8 is shown and described.

20 The head 8 in its formation has the end wall 11 and an outwardly extending annular flange 12 at the free end of the side wall 9, and the end wall having the filling and dispensing opening 13 for the reception of a closure cap, not shown.

25 After the head 8 has been formed to provide the right-angular flange 12 on the outer end of the side wall 9 thereof as shown in Fig. 2, forming rolls 14—15 are engaged against the side wall 9 of the head to provide an inwardly disposed relatively deep recess 16 beneath the flange 12, and to form an annular groove 17 in the side wall 9 adjacent and above the end wall 11 of the head 8 as shown in Fig. 3.

30 The body wall 11a is operated on at its upper end to provide an outwardly disposed depending annular flange 18, and said flange may if required, be downwardly bent against the wall as shown at 19 in dotted lines in Fig. 4.

35 The flange 12 of the head 8 is then operated on by dies or other forming devices to deflect the flange to the approximate angle shown in Fig. 4a, in readiness to receive the depending flange 18 of the body wall 11a thereunder, when the head is forceably inserted in the upper end of the container body 7, as shown in Fig. 5.

40 After the insertion of the head 8 in the container body 7, a die 20 having an annular deflecting flange part 21 is engaged to operate on the flanged ends of the head and body, ready to 45 downwardly press and fold the respective flanges 12 and 18 into the annular recess 16 of the side wall 9 of the head, as illustrated in Fig. 5.

45 The next operation is to inwardly press the flanges 18—12 and the portion 22 of the body 50 wall 11a against which the flange 18 will abut,

into the recess 16 of the head with the flange 12 of the head in flush alignment with the outer surface of the body wall 17a of the container, thus completing the formation of this improved chime 10 as shown in Fig. 6, however, after the inner surfaces of the folded and crimped together parts have been soldered or tinned to provide an extremely tight joint.

Simultaneously with the crimping or folding 10
securance of the flanges 18-12 in the recess 16
an annular groove 23 may be formed in the body
wall 17a to press an inwardly disposed bead 24
into seating engagement with the groove 17 of
the head side wall 9 to form a seal-tight joint
between the head and body wall outwardly of 15
and adjacent the end wall 11 of the head 8, also
as shown in Fig. 6.

The aforescribed method of making this improved chime end construction to metallic containers and the like provides an extremely strong 20 chime at each end of the container without the inclusion of a reinforcing or clamping ring heretofore used in chime construction and by reason of the outer surface of the container being flush, sliding of containers one upon another is enhanced.

Obviously, constructional modifications of the

structure and/or method shown are possible without departing from the spirit and scope of the present invention and therefore it is to be understood that it is not necessary to limit the invention by the terms used in the foregoing description.

What I claim is:

1. The method of making a container chime consisting of forming a flanged counter-sunk head with a pair of annular recesses in the side wall thereof, of flanging an end of a container body, of mounting the head in the flanged end of the body, of pressing the flanges of the head and body into one of the recesses of the head, and of pressing the body into conformity with the other recess of the head.

2. The method of making a container chime consisting of forming a flanged counter-sunk head with a pair of annular recesses in the side wall thereof, of flanging an end of a container body, of mounting the head in the flanged end of the body, and of simultaneously pressing the flanges of the head and body into one of the recesses of the head and the body into conformity with the other recess of the head.

LOUIS B. WACKMAN.
